UNITED STATES PATENT OFFICE

SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY

RETAINING DEVICE FOR PLATE VALVES

Application filed December 1, 1928. Serial No. 323,077.

This invention relates to compressors, but more particularly to a retaining device adapted to secure the plate valves in the compressor.

One object of the invention is to facilitate the operation of installing a plate valve, its retaining means and the valve controlling means, such as a valve lifter, in the compressor head as a unit.

Other objects will be in part obvious and in part pointed out hereinafter.

The accompanying drawing illustrating the invention is a vertical sectional elevation of a compressor head and a plate valve illustrating a practical application of the invention.

Referring more particularly to the drawing, A represents a portion of a compressor head having an inner wall B and an outer wall C suitably spaced with respect to each other to form a passage D through which the element intended to be compressed may flow to the cylinder inlet, such as a valve opening E, in the inner wall B. The valve opening E is adapted to accommodate a plate valve F which may, as illustrated, be an inlet valve comprising a valve seat G, a valve plate H and a stop plate J. The inlet valve may be of any well known type and its component parts may be held together in any suitable manner as for instance by a bolt K which extends through the valve seat G, the valve plate H and the stop plate J and is provided with a nut L whereby the parts comprising the plate valve are clamped securely together.

Formed in the outer wall C of the head A is a cover opening O to receive an extension P of a cover Q which forms a closure for the cover opening O. The cover Q is preferably secured to the compressor head A by means of bolts R which extend through a flange S of the cover Q and are threaded into the outer wall C of the head.

A difficulty frequently encountered in installing plate valves and their adjuncts in compressor heads is that of maintaining these elements in coaxial relationship during the process of installation, particularly where the valve openings lie in inclined positions. This

is due to various causes, such as the multiplicity of parts comprising the valve and its retaining means and to the difficulty of viewing the exact arrangement of the parts when in position between the inner and outer walls. 55 These limitations suggest the desirability of enabling the various elements comprising the valve mechanism to be assembled prior to the installation in the compressor head. In order therefore to facilitate the operation of installing the device in the compressor, a hollow body T having an outer wall U and an inner concentric wall V is disposed on the valve seat G and carries at its front end an annular flange W which encircles and engages 60 the adjacent end of the valve seat G. On the inner surface of the outer wall U are lugs X having apertures Y to accommodate bolts Z which may be threaded into the valve seat G for securing the body T to the valve seat. 65

Inasmuch as the distance between the inner and outer walls of the compressor head, and therefore the distance between the openings E and O, may vary and in view of the fact that it is essential that fluid tight joints should be maintained between the compressor head and the elements disposed in the valve and cover openings, allowance should be made for a degree of longitudinal movement between the body T and the cover Q. In order 70 to permit of such movement of these elements, the outer end of the body T is provided with a shallow recess b, the bounding surface c of which lies in the same plane as the outer wall U. The recess b serves as a seat for an inner cover d which is secured to the body T by means of screws e and extends slidably with its free end into a bore f in the extension P of the cover Q. The inner cover d in this instance has a central hub g against which pressure may be applied by a set screw h threaded into the outer cover Q for pressing the valve seat G firmly in position in the inner wall B. 75

At times it may be advantageous to employ free air unloading means for unloading the 95 compressor when the pressure in the receiver into which the compressed fluid is delivered reaches a certain predetermined value. The present invention lends itself readily to this type of unloading device, and for illustrative 100

purposes an unloading device is shown in the form of a plunger *j* guided slidably by the wall *V*. The plunger *j* carries at its inner ends fingers *k* which extend through the valve seat *G* to a point near the valve plate *H* against which they are adapted to press for unseating the valve plate. The plunger *j* may be provided with a recess *o* to receive a spring *p* which bears with one end against the valve seat *G* and with its other end against the roof of the recess *o* for normally holding the fingers *k* free from the valve plate *H*.

In order to actuate the plunger *j* through the medium of pressure fluid, a diaphragm *q* is clamped at its edge between the inner cover *d* and the body *T* and bears with its intermediate portion against the end of the plunger *j*.

The inner cover *d* may be slightly concave at the portion overlying the end of the plunger *j* to form a pressure chamber *r* into which pressure fluid may be introduced for actuating the plunger *j* and consequently the fingers *k* to unseat the valve plate *H*. In the present instance such pressure fluid is introduced into the space between the inner cover and the diaphragm through a threaded passage *s* in the hub *g* which registers with a passage *t* in the set screw *h*, and the passage *t* in turn is in communication with a suitable supply connection *u* threaded into the end of the set screw.

In order to assure against leakage between the end of the set screw and the hub *g*, a tapered or ball seat *v* may be formed on the end of the hub *g* to accommodate a correspondingly shaped end *w* of the set screw which cooperates with the seat *v* to form a fluid tight joint around the adjacent openings of the passages *s* and *t*.

During the operation of installing the valve mechanism in the compressor head *A*, the plunger *j* with the spring *p* may first be disposed in the body *T*, and the said body *T* may be secured to the valve seat *G* by means of the screws *Z*. In this way the body *T* and the valve seat will be secured firmly together. After these parts have been thus assembled, the diaphragm *q* and the inner cover *d* may be placed in position in the recess *b* and secured to the body *T* by means of the screws *e*. Thereafter the cover *Q* may be disposed on the inner cover *d* and a bolt of any suitable length may be extended through the cover *Q* and threaded into the passage *s* to secure the cover *Q* to the inner cover *d*.

When assembled in the manner described, the valve and the associated elements will be in their proper relative positions and may therefore readily be installed in the compressor head. After the valve and the connected parts have been installed in the compressor head and the bolts *R* are threaded into the outer wall *C* to secure the cover *Q* in position, the bolt previously used for connecting

the inner cover to the outer cover may be removed and the set screw *h* may be substituted therefor.

From the foregoing description, it will be readily seen that the joints between the valve seat and the inner wall and those between the outer cover and the outer wall may be effectively sealed against leakage and that either one of these joints may be tightened separately without disturbing the other joint or joints.

I claim:

1. In a compressor, the combination of a compressor head and a plate valve, said head having an inner wall with a valve opening and an outer wall with a cover opening coaxial with the valve opening, a plate valve in the valve opening, a cover forming a closure for the cover opening and having a bore, a body interposed between the plate valve and the cover and in engagement with the plate valve, an inner cover secured to the body and lying wholly within the bore for holding the plate valve coaxial with the cover, and a plurality of bolts engaging the body and threaded into the plate valve for securing said body to the plate valve, thereby enabling the plate valve and the cover to be disposed in the compressor head as a unit.

2. In a compressor, the combination of a compressor head and a plate valve, said head having an inner wall with a valve opening and an outer wall with a cover opening coaxial with the valve opening, a cover forming a closure for the cover opening and having a bore, a body having an outer wall in engagement with the plate valve and an integral inner guide, a valve lifter disposed slidably in the guide, an inner cover lying wholly within the bore and being seated on the outer wall of said body for holding the body and the plate valve in coaxial alignment with the cover, said inner cover providing a telescopic adjustment to compensate for variations in the distance between the inner and outer walls of the head, means for securing the inner cover to the body, and means associated with the cover to exert a pressure on the inner cover for securing the plate valve in the valve opening.

In testimony whereof I have signed this specification.

SNOWDEN B. REDFIELD.
